UNITED STATES PATENT OFFICE.

LESLIE H. KAMPER, VICTOR E. ADLAND, AND WILLIAM BARTHOLOMEW, OF CHICAGO,
ILLINOIS.

DRY-ROOM TUMBLER.

1,405,594.

specification of Letters Patent.

Patented Feb. 7, 1922.

Application filed March 10, 1920. Serial No. 364,648.

To all whom it may concern:

Be it known that we, LESLIE H. KAMPER, VICTOR E. ADLAND, and WILLIAM BARTHOLOMEW, residing at Chicago, in the county 5 of Cook and State of Illinois, have invented certain new and useful Improvements in Dry-Room Tumblers, of which the following is a specification.

This invention relates to dry-room tumblers.

It has been the practice for some time to dry washed clothes in dry-room tumblers by directing a supply of hot air thereto. Clothes are dried relatively quickly in this 15 type of device, but it has been found that clothes dried by hot air in this manner have a very peculiar and repulsive odor.

One object of this invention is to overcome this undesirable feature in a simple, 20 inexpensive and novel manner.

Another object is to provide simple and efficient means for deodorizing or refreshing washed clothes in a dry-room tumbler.

The invention is illustrated on the accompanying sheets of drawings, in which—

Figure 1 is a vertical sectional view of a dry-room tumbler embodying our invention; and

Figure 2 is a partial sectional view and 30 partial elevational view taken in the planes of irregular line 2—2 of Figure 1.

The dry-room tumbler includes an outer casing 10 provided with a hinged door 11, whereby clothes may be placed into and 35 withdrawn from the rotatable receptacle 12 mounted within the casing 10. Heating coils 13 are placed within walls 14 and 15 of the casing for heating air which is drawn thereto by means of any suitable fan 16, 40 said fan being mounted in a casing 17 which is directly connected with the heating compartment, the passage of air from the fan to the heating compartment being controlled by a valve or damper 18 pivotally 45 mounted at 19.

This valve 18 has a depending arm 20 which is connected by rods 21 and 22 to the lower end of an arm 23 of a hand operated lever 24, whereby the valve 18 may be opened 50 or closed readily. Another valve 25 is located at the outlet portion of the hot air supply conduit 26, and not only controls the supply of hot air passing from the hot air conduit 26 into the main casing of the tumbler or the rotary member 12 of the tumbler, 55

but also controls any exhaust from the main casing of the dry-room tumbler through the exhaust stack 27. This valve or damper 25 is pivotally mounted at 28 and has an arm 29, to which is connected an adjustable connecting means 30, which in turn is connected to another arm 31 of the lever 24, the latter being pivoted at 32.

As shown in Figure 1 of the drawings, and assuming that the fan 16 is in operation, air 65 is forced from the fan casing 17 past the heated coils 13 out through hot air conduit 26 past valve 25 into the main tumbler casing, in which the rotary member 12 containing wet clothes to be dried is mounted. As 70 the rotary member continues to rotate and hot air blown into intimate contact with the clothes therein, the latter become dried in a relatively short length of time; but, as stated hereinabove, such clothes dried in the manner indicated are left with a repulsive odor.

To deodorize and refreshen the clothes dried in the tumbler, we force a supply of cold air into intimate contact with the dried clothes. This blast of cold air is preferably 80 supplied from an independent source, for instance, through a main cold air supply conduit 33 and a plurality of branch conduits 34 which communicate with the lower part of the rotary member 12, at widely dispersed 85 points, whereby cold air is directed in subdivided streams through and into intimate contact with the whole mass of dried clothes, and preferably in a direction opposite to that in which the hot air flows. The cold 90 air exhausts through the stack 27. It will be understood that during the time cold air is being supplied to the clothes, the supply of hot air thereto is cut off.

The control of the hot air is preferably 95 effected through the operating lever 24. Referring particularly to Figure 1, it will be noted that if the lever 24 is moved to the left from the position shown, the valve or damper 25 will be moved into a position to 100 check the flow of hot air through the conduit 26. Lever 24 may also be so connected that the valve or damper 18 will, at the same operation, be moved into its closed position to shut off the supply of air from the fan 16 to the hot coils 13. When the valves are 105 in these positions, cold air may be supplied through the conduits in question for refreshening the dried clothes.

When the cold air is cut off in any suitable 110

manner, and it is desired to direct hot air to the clothes, valve 18 may be opened any desired degree as may be valve 25. If desired, the valve 25 may be moved into position such 5 that the exhaust stack 27 is completely cut off from the main casing of the tumbler.

Preferably, the supply of cold air through the conduits 33 and 34 is controlled by a valve 35 operable in a conduit 36 directly 10 connected to the conduit 33, said valve having a stem 37 to which is connected an arm 38, which in turn is operatively connected to the arm 23 of lever 24. In this way, valve 35 for admitting or excluding the reverse 15 flowing cold air may be operated simultaneously with the valve 25 that controls the hot air; and if the valve 18 is employed, all of the valves 18, 25 and 35 may be simultaneously controlled. Preferably, when hot 20 air is supplied for drying purposes, cold air is cut off and when cold air is supplied for freshening the clothes, the hot air is cut off.

It is apparent that there may be various 25 modifications of the invention and it is our intention to cover all modifications of the invention falling within the spirit and scope of the following claims.

We claim:

- 30 1. In a dry-room tumbler, means for supplying a drying medium to the clothes in said tumbler, and independent means for subjecting said clothes in said tumbler to a fresh aerating medium.
- 35 2. In a dry-room tumbler, a drying chamber, means for supplying a drying medium to the drying chamber, and independent means for subjecting the contents of said chamber to a fresh aerating medium; said 40 independent means having a plurality of delivery passages through which it delivers said freshening medium in subdivided form and to distributed parts of the drying chamber.
- 45 3. In a dry-room tumbler, means for supplying a drying medium flowing in one direction through the clothes in said tumbler, means for treating said clothes in said tumbler to a fresh aerating medium flowing in 50 another direction therethrough, and means for selectively controlling the delivery of such mediums to said tumbler.
- 55 4. In a dry-room tumbler, the combination of a receptacle in which clothes are dried, means for causing hot air to flow through said receptacle in one direction for drying the clothes, and an independent means for causing cold air to flow through said receptacle in another direction for 60 freshening said clothes.
- 65 5. In a dry-room tumbler, the combination of a receptacle in which clothes are dried, means for causing hot air to flow through said receptacle in one direction for drying 65 the clothes, an independent means for caus-

ing cold air to flow through said receptacle in another direction for freshening said clothes, and independent means for controlling the hot and cold air supplies.

6. In a dry-room tumbler, the combination 70 of a receptacle in which clothes are dried, means for causing hot air to flow through said receptacle in one direction for drying the clothes, an independent means for causing cold air to flow through said receptacle 75 in another direction for freshening said clothes, independent means for controlling the hot and cold air supplies, and a common means reciprocally actuating the two air-controlling means. 80

7. In a dry-room tumbler, the combination 85 of a receptacle in which clothes are dried, means for causing hot air to flow through said receptacle in one direction for drying the clothes, an independent means for causing cold air to flow through said receptacle in another direction for freshening said clothes, and independent means for controlling the hot and cold air supplies; the hot air supply means comprising an air heating 90 compartment, means for passing air from the heating compartment to the clothes-containing receptacle, and means for controlling both ingress and egress of the air of said heating compartment. 95

8. In a dry-room tumbler, the combination 100 of a receptacle in which clothes are dried, means for causing hot air to flow through said receptacle in one direction for drying the clothes, an independent means for causing cold air to flow through said receptacle 105 in another direction for freshening said clothes, and independent means for controlling the hot and cold air supplies; the hot air supplying means comprising an air heating compartment, means for passing air from the heating compartment to the clothes-containing receptacle, means for controlling both ingress and egress of the air of said heating compartment, means for controlling the supply of cold air to the clothes-containing receptacle, and a common actuating means for all of said air controls. 110

9. In a dry-room tumbler, the combination 115 of a main casing, a receptacle therein in which clothes are dried, a hot air supply for drying said clothes in said receptacle, a valve for controlling the supply of hot air, a cold air supply for purifying the dried clothes, a valve for controlling the supply of cold air, 120 and control means operatively connected to said valves.

10. In a dry-room tumbler, a main casing, a rotary member mounted therein for containing clothes, a heating compartment, 125 means for supplying air to said heating compartment, a valve for controlling the supply of air to said heating compartment, a valve for controlling the supply of air from said heating compartment to said 130

clothes-containing receptacle, means for supplying cold air to said clothes-containing receptacle for purifying the clothes, a valve for controlling the supply of cold air, and a 5 control member operatively connected to all of said valves.

11. In a dry-room tumbler, a main casing, a rotary member mounted therein for containing clothes, a heating compartment, means 10 for supplying air to said heating compartment, a valve for controlling the supply of air to said heating compartment, a valve for controlling the supply of air from said heating compartment to said clothes-containing

receptacle, means for supplying cold air to 15 said clothes-containing receptacle for purifying the clothes, a valve for controlling the supply of cold air, and a control member for controlling all of said valves simultaneously, one of said valves controlling the supply of 20 hot air to said receptacle and the flow of cold air therefrom.

Signed at Chicago, Illinois, this 4th day of March, 1920.

LESLIE H. KAMPER.

VICTOR E. ADLAND.

WILLIAM BARTHOLOMEW.
